BATHING CAP

Thomas J. Howland, Long Branch, N. J.

Application April 13, 1940, Serial No. 329,421

11 Claims. (Cl. 2—68)

This invention relates to articles of wearing apparel, such as bathing caps, rubber boots, and the like, and is concerned more particularly with a novel article of this character which may be worn with comfort and at the same time is extremely resistant to the seepage of fluid into the article. The article of my invention is of a simple construction adapted for manufacture at low cost and is substantially water proof by reason of its inclusion of a novel ribbed structure which prevents the passage of water into the article under the edges thereof, even when the article is subjected to severe use. This application is a continuation-in-part of my co-pending application Ser. No. 222,127, filed July 30, 1938, which issued July 2, 1940, as Patent No. 2,206,402.

For illustrative purposes, the principles of the invention will be described and illustrated in connection with a bathing cap, although it will be understood that the invention is not limited to this use but is applicable to other articles of wearing apparel as well.

In bathing caps as commonly made, there is a tendency for water to seep into the interior of the cap body between the edge of the cap and the head of the wearer, the amount of seepage depending on how tightly the cap fits the head. It has been proposed heretofore to reduce the amount of seepage by providing on the inside of the cap body one or more encircling ribs which extend around the cap near its lower edge so as to engage the head of the wearer. These ribs have taken various forms, but in nearly all instances they extend straight inwardly from the cap body and at their free ends are flat, concave or convex. While ribs of this type serve to reduce the amount of seepage, they are not entirely satisfactory for the reason that they have a relatively great resistance to stretching and do not readily bend or incline so as to accommodate the size and the irregularities of the wearer's head, whereby they tend to impair the comfort of the wearer. This is especially so when a pair of parallel encircling ribs are employed which are braced by cross ribs, since the latter add materially to the stiffness of the encircling ribs.

Another form of encircling rib employed heretofore is relatively thin and flexible and projects inwardly a substantial distance from the inner surface of the cap body, so that when the cap is applied to the head the rib is forced toward a flat position against the inner surface and only one side of the rib contacts the head. While

caps employing encircling ribs of this form are generally more comfortable than those having relatively stiff ribs, they are not water-tight in normal use.

The present invention, therefore, is directed to the provision of a novel bathing cap which overcomes these objections to prior caps and which is both comfortable and water proof to a high degree. A cap made in accordance with my invention comprises a cap body of any desired form made of rubber, or the like, and having at least one rib on the inside of the cap extending substantially parallel to the edge and preferably encircling the cap. The rib is flexible and may normally extend straight inwardly from the cap body or at an oblique angle thereto, but in either case it is characterized in that it may be deflected laterally, preferably by a biasing edge at its free end located on one side of its center line. Thus, when the cap is put on, the off-center edge is the first part of the rib to engage the head of the wearer, and by reason of the flexibility and location of this edge it is upset in the direction in which it is off-center and causes the rib to deflect in that direction. Since it is deflectable laterally, the rib readily adapts itself to the contour of the head by deflecting more or less under the action of the pressure of the head against the rib. However, the main body of the rib is sufficiently stiff to prevent the rib from upsetting completely and maintains the lagging side of the deflected rib firmly against the head.

On the lagging side of the rib is a longitudinal groove disposed between the free end portion of the rib and the adjacent part of the cap body. Preferably, the free end portion of the rib is inclined from the off-center edge toward the cap body, and the groove extends into the side of the rib under the inclined, free end portion. The sides of the groove may be constituted by the body of the rib or by longitudinal fins projecting from the side of the rib, or by both, but in any case the deflection of the rib under the action of the off-center edge causes the lagging side of the rib near its free end to contact the head of the wearer so that the side edges of the groove are pressed against the skin. The pressure between the edges of the groove and the head of the wearer is effected partly by the cap body and partly by the tendency of the rib to straighten itself, and as a result of this pressure and the deflection of the rib, the sides of the groove are forced apart and the groove is made shallower so that a suction is created therein.

Due to the suction provided at the side of the rib adjacent the head, the rib is caused to engage the head more snugly and seepage of water into the cap is more effectively prevented. The sides of the groove may spread apart more or less under the pressure of the rib against the head, whereby the rib acts as a cushion to accommodate irregularities in the shape of the head, absorb shock, etc. In the preferred construction, a second rib is arranged on the inside of the cap body parallel to the first rib, and the off-center edge of the upper rib is disposed above its centerline, while the off-center edge of the lower rib is disposed below the centerline of the latter, so that the ribs are deflected away from each other and a suction space is created between them which supplements the suction effect in the ribs themselves. If desired, the two ribs may be braced by cross ribs which limit the deflection of the encircling ribs.

For a better understanding of the invention reference may be had to the accompanying drawing, in which

Fig. 1 is a side view of one form of a new bathing cap made in accordance with the invention;

Fig. 2 is an enlarged sectional view on the line 2—2 in Fig. 1;

Fig. 3 is a plan view of a section of the encircling ribs shown in Fig. 2;

Fig. 4 is an enlarged sectional view of one of the encircling ribs shown in Figs. 2 and 3;

Figs. 5, 6 and 7 are cross-sectional views of modified forms of the encircling rib; and

Fig. 8 is an enlarged cross-sectional view of the ribs shown in Figs. 2 and 3 illustrating the action of the ribs when the cap is applied to the head.

Referring to the drawing, the numeral 10 designates a bathing cap of any desired form comprising a hollow body 11 made of rubber, or the like, the body being shaped to fit the general contour of the head. Secured along the inside edge of the body 11 is a rubber cup band comprising a base 12 and two pairs of spaced, parallel encircling ribs 13, the ribs extending generally parallel to the edge of the cap. Between each pair of encircling ribs are cross ribs or bracing ribs 14 which may extend at oblique angles to the encircling ribs in zig-zag fashion. The cross ribs 14 serve to brace the encircling ribs and tend to prevent them from being bent over completely against the cap body when the cap is worn.

The uppermost encircling rib 13, as shown, extends inwardly from the cap body at right angles thereto and terminates at its free end in a relatively thin edge 15 located on the upper side of the center line of the rib. From the edge 15, the free end portion 16 of the rib slopes downwardly and toward the cap body and terminates in a relatively thin edge 17 on the lower side of the rib. The edge 17 partly defines a longitudinal groove 18 disposed under the inclined end portion 16 of the rib, preferably a substantial distance from the base of the rib.

The rib 13 directly below the uppermost encircling rib terminates in a thin edge 15' located on the lower side of its center line and is formed with an oblique end portion 16' sloping upwardly toward the cap body and terminating in a relatively thin edge 17' which partly defines a groove 18' in the upper side of the rib. Thus, the free end portions of the two ribs are inclined in oppo-

site directions, and the two grooves 18 and 18' face each other.

The pair of encircling ribs 13 near the lower edge of the cap are identical with the upper pair 5 and need not be described in detail.

When the cap is worn, the free ends of the encircling rib 13 are engaged by the head 29 of the wearer and are upset, as shown in Fig. 8. More particularly, the off-center edges 15 and 15' are the parts of the ribs which first engage the head, and by reason of the flexibility of these edges and their locations, each edge is deflected by the head in the direction in which it is off-center. That is, the edge 15 of the uppermost encircling rib is deflected upwardly and upsets this rib so that the lagging or lower side of the rib engages the head. Thus, the side edges of the groove 18 are pressed against the skin by the cap body and by the tendency for 10 the rib to straighten itself, so that these edges of the groove are spread apart and the groove becomes shallower. As a result, a suction is 15 created in the groove which prevents shifting of the rib against the skin and more effectively 20 resists seepage of water into the cap body. It will be observed that the upsetting of the rib 25 causes the inclined end portion 16 to lie substantially flush against the head and causes the lower edge 19 of the groove to engage the head 30 with a substantially line contact, whereby the groove is effectively sealed.

The encircling rib immediately below the uppermost rib 13 is deflected downwardly, since its initial skin-contacting edge 15' is on the lower 35 side of its center line. Accordingly, the side edges of the groove 18' are pressed against the skin and a suction effect is provided in this groove as well. Also, since the end portions of the two encircling ribs are bent in opposite directions and the space between these ribs is made 40 shallower, a suction is created in this space which supplements the suction effect in the grooves 18 and 18'. The tendency for the two encircling 45 ribs to deflect away from each other is opposed by the cross ribs 14 which lend a certain degree 50 of stiffness to the bodies of the encircling ribs so that only their end portions are substantially deflected. In the deflected positions of the two upper ribs, the suction space between them is 55 separated from the suction spaces in the grooves 18 and 18', so that if the suction in one of the spaces is broken for any reason the suction in the other spaces will not be affected.

The lower pair of encircling ribs 13 is deflected 60 in the same manner as the upper pair, as shown in Fig. 8.

With this construction, the free end portions of the encircling ribs are deflected more or less depending on the pressure exerted by the ribs 65 on the head of the wearer, and, therefore, the cap may readily accommodate itself to the contour of the head. Because of the off-center edges at the free ends of the encircling ribs, the latter are always deflected in such a manner that each 70 rib is biased away from the rib with which it is paired and in a direction such that the side edges of its groove are forced against the skin, whereby the desired suction is provided between the ribs and in their respective grooves which acts 75 to maintain the engagement of the ribs with the skin, secure the cap against shifting on the head, and prevent seepage of water which might otherwise occur. The grooves 18 and 18' serve not only to provide the desired suction effect in the ribs themselves but also to cushion the edge

portion of the cap on the head, since the greater the pressure of the cap against the head, the more the side edges of the respective grooves will spread to accommodate the pressure.

While I have shown a cup band 12 inside the cap having four encircling ribs, it will be understood that only one encircling rib or any other number may be employed, although I prefer to use at least one pair of encircling ribs so as to form a suction space between them. The cross ribs 14 may be straight or concave at their free ends, instead of convex, as shown, and may be arranged to form suction cups which are diamond-shaped, square, oval, etc., instead of triangular. Also, the cup band 12 may be made integral with the cap body or it may be made in a separate piece and cemented to the body.

The cup band shown in Fig. 5 comprises a base 22 on the inside of the cap body, and an encircling rib 23 projecting inwardly from the base. The rib 23 is normally inclined at an oblique angle to the base 22 and is formed at its inner end with an initial skin-contacting edge 24 located on one side of the center line of the rib. From the edge 24, the end portion of the rib slopes upwardly toward the base, as shown at 25, so that the free end of the rib gradually increases in thickness. In the upper or lagging side of the rib is a longitudinal groove 26, the edges of which are constituted by fins 27 and 28 projecting from the side of the rib. The fin 27 is disposed at the upper edge of the inclined end portion 25, while the fin 28 is between the fin 27 and the base of the rib. When the cap is applied to the head, the off-center edge 24 is deflected downwardly so as to tilt the end portion of the rib and cause the fins 27 and 28 to contact the skin. Due to the pressure of the rib against the head, fins are forced apart and a suction is created in the groove 26 which is sealed by the ends of the fins.

The band shown in Fig. 6 comprises a base 30 on the inside of the cap body, and an encircling rib 31 projecting at right angles to the base and terminating at its free end in a thin, initial skin-contacting edge 32 disposed on one side of the center line. The free end portion of the rib slopes upwardly from the edge 32 toward the base 30, as shown at 33, and terminates in a relatively thin edge 34 on the upper side of the rib. A longitudinal groove 35 is formed in the upper side of the rib and is defined in part by the thin edge 34 and in part by a longitudinal fin 36 disposed between the groove and the base 30. It will be apparent that when the off-center edge 32 contacts the head, it is deflected so as to tilt the rib 31 downwardly. As a result, the lateral edge 34 and the side fin 36 are pressed against the skin and forced apart so as to create the desired suction effect in the groove 35.

In the construction shown in Fig. 7, an encircling rib 38 extends inwardly from the cap body and is normally inclined at an oblique angle to the adjacent surface of the cap. The rib is relatively thick at its base but tapers toward its free end where it terminates in an enlargement 39. This enlargement projects upwardly and away from the base so as to form a longitudinal groove 40 in the upper or lagging side of the rib, the groove being defined in part by the overhanging portion of the enlargement 39 and in part by the lagging side of the tapered portion of the rib. The enlargement 39, as shown, terminates in a relatively thin, initial skin-contacting edge 41 located on the lower side of the cen-

ter line of the rib. When the edge 41 contacts the skin, it deflects the end portion of the rib downwardly so that the lagging side of the tapered part of the rib engages the skin. As a result, the edge 41 and the opposite side of the groove 40 are forced apart and the desired suction is created in the groove.

It will be apparent that the cross ribs may take other forms and may be disposed in other arrangements than those illustrated. For example, they may extend at right angles to the encircling ribs or they may cross each other. Also, they may extend only partly across the space between the encircling ribs or, instead of projecting into this space, they may extend from the side of each encircling rib remote from the adjacent encircling rib. The term "fin" as used herein is intended to denote any protruding edge sharp or rounded, formed by two intersecting surfaces.

In the foregoing description and in the following claims, the expression "centerline of the rib" is intended to denote an imaginary line bisecting the outer end of the rib proper, that is, the end of the rib adjacent the cap body, the line being perpendicular to the adjacent surface of the cap body or other rib supporting member. The expression "off-center," as used in reference to the initial skin-contacting edge of the rib, means that this edge is offset from the "centerline" on one side thereof. The word "side," as used in the claims in reference to the rib, is intended to denote one of the lateral faces of the rib disposed between its free end portion and the rib support, as distinguished from the free end of the rib, which may be a straight or an inclined surface, as in Figs. 4, 5 and 6, or a thin edge, as in Fig. 7.

I claim:

1. In an article of apparel comprising a hollow body having an opening therein, an elastic rib on the inside of the body extending generally parallel to the margin of the opening and projecting inwardly with its free end terminating in an initial skin-contacting edge located on one side of the center line of the rib, the rib being flexible and readily deflectable laterally whereby said edge when pressed against the skin is deflected in the direction in which it is off-center and tilts the rib in said direction, the rib having a longitudinal groove in its lagging side confined to said lagging side and disposed between the free end portion of the rib and the adjacent part of the body, the side edges of the groove being operable to contact the skin when the rib is deflected and thereby seal the groove.

2. In an article of apparel comprising a hollow body having an opening therein, an elastic rib on the inside of the body extending generally parallel to the margin of the opening and projecting inwardly with its free end terminating in an initial skin-contacting edge located on one side of the center line of the rib, the rib having its end portion inclined from said off-center edge toward the body and being flexible and readily deflectable laterally whereby said edge when pressed again the skin is upset in the direction in which it is off-center and tilts the rib in said direction, the rib having a longitudinal groove in its lagging side confined to said lagging side and disposed between said inclined end portion and the adjacent part of the body, the side edges of the groove being operable to contact the skin when the rib is deflected and thereby seal the groove.

3. In an article of apparel comprising a hollow body having an opening therein, an elastic rib on the inside of the body extending generally parallel to the margin of the opening and projecting inwardly with its free end terminating in an initial skin-contacting edge located on one side of the center line of the rib, the rib having its end portion inclined from said off-center edge toward the body and being flexible and readily deflectable laterally whereby said edge when pressed against the skin is upset in the direction in which it is off-center and tilts the rib in said direction, said inclined end portion terminating in an edge partly defining a longitudinal groove in the lagging side of the rib under the end portion and confined to said lagging side, the side edges of the groove being operable to contact the skin when the rib is deflected and thereby seal the groove.

4. In an article of apparel comprising a hollow body having an opening therein, an elastic rib on the inside of the body extending generally parallel to the margin of the opening and projecting inwardly with its free end terminating in an initial skin-contacting edge located on one side of the center line of the rib, the rib being flexible and readily deflectable laterally whereby said edge when pressed against the skin is deflected in the direction in which it is off-center and tilts the rib in said direction, the rib having a pair of spaced, longitudinal fins on the lagging side thereof partly defining a suction space between them, the fins being operable to contact the skin when the rib is deflected and thereby seal the groove.

5. In an article of apparel comprising a hollow body having an opening therein, an elastic rib on the inside of the body extending generally parallel to the margin of the opening and projecting inwardly with its free end terminating in an initial skin-contacting edge located on one side of the center line of the rib, the rib being flexible and readily deflectable laterally whereby said edge when pressed against the skin is deflected in the direction in which it is off-center and tilts the rib in said direction, the rib having a longitudinal groove in the lagging side thereof confined to said lagging side and disposed between the free end portion of the rib and the adjacent part of the body, the rib also having fins along the side edges of the groove operable to contact the skin when the rib is deflected and thereby seal the groove.

6. In an article of apparel comprising a hollow body having an opening therein, an elastic rib on the inside of the body extending generally parallel to the margin of the opening and normally projecting inwardly from the body at an oblique angle to the adjacent surface of the body, the rib being flexible and readily deflectable laterally whereby the free end thereof when pressed against the skin is deflected in a direction in which the rib is inclined and tilts the rib in said direction, the rib having a longitudinal groove confined in the side thereof remote from the body and disposed between the free end portion of the rib and the adjacent part of the body, the side edges of the groove being operable to contact the skin when the rib is deflected and thereby seal the groove.

7. In an article of apparel comprising a hollow body having an opening therein, an elastic rib on the inside of the body extending generally par-

allel to the margin of the opening and projecting inwardly with its free end terminating in an initial skin-contacting edge located on one side of the center line of the rib, the rib being flexible and readily deflectable laterally whereby said edge when pressed against the skin is deflected in the direction in which it is off-center and tilts the rib in said direction, the free end portion of the rib being inclined away from said edge toward the body, the rib having a longitudinal groove confined in the lagging side thereof under said end portion and defined partly by one edge of said end portion and partly by a laterally extending fin on the lagging side of the rib, said last edge and fin being operable to contact the skin when the rib is deflected and thereby seal the groove.

8. In an article of apparel comprising a hollow body having an opening therein, an elastic rib on the inside of the body extending generally parallel to the margin of the opening and projecting inwardly from the body, the rib having a laterally facing, longitudinal groove on one side thereof, the side of the groove remote from the body being constituted by an overhanging part of the rib forming an initial, skin-contacting edge operable on contact with an object in the body to deflect the rib toward the side opposite said groove, whereby the side edges of the groove contact the skin and seal the groove.

9. In an article of apparel comprising a hollow body having an opening therein, an elastic rib on the inside of the body extending generally parallel to the margin of the opening and projecting inwardly from the body, the rib tapering from the base thereof to an enlargement at the free end of the rib, the enlargement projecting at an oblique angle from the main body of the rib and defining with said rib body a longitudinal groove on one side of the rib, the enlargement terminating in an initial skin-contacting edge disposed on one side of the center line of the rib and being operable when pressed against the skin to deflect the rib in the direction in which said edge is off-center and thereby tilt the rib in said direction, the side edges of the groove being operable to contact the skin when the rib is deflected and thereby seal the groove.

10. In an article of apparel comprising a hollow body having an opening therein, a flexible elastic rib on the inside of the body extending generally parallel to the margin of the opening and projecting inwardly from the body, and a pair of longitudinal fins on one side of the rib confined to said side and disposed between the free end portion of the rib and the adjacent part of the body and partly defining a suction space on the side of the rib, the rib being readily deflectable laterally to cause the fins to contact the skin and seal the suction space.

11. In an article of apparel comprising a hollow body having an opening therein, a flexible elastic rib on the inside of the body extending generally parallel to the margin of the opening and projecting inwardly from the body, the rib having a longitudinal groove in one side thereof confined to said side and disposed between the free end portion of the rib and the adjacent part of the body, the rib being readily deflectable laterally to cause the side edges of the groove to contact the skin and thereby seal the groove, the groove providing a suction space remote from said end portion.

THOMAS J. HOWLAND.
